UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,025,990.

Specification of Letters Patent.

Patented May 14, 1912.

Application filed May 22, 1907. Serial No. 375,143.

To all whom it may concern:

Be it known that I, WILLIAM H. MUZZY, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash registers, and has more particular relation to improvements in printing attachments of the same.

The principal object of the invention is to provide means whereby the proprietor may secretly adjust the printing mechanism upon leaving his place of business, and upon his return thereto, so that all transactions registered in the interim can be separated from other transactions.

20 A further object of the invention is to provide means for designating the time of day on the recording strip in the register.

With these and incidental objects in view, the invention consists in certain novel features of construction and combinations of parts, the essential elements of which are set forth in appended claims and preferred forms of embodiment of which are herein after specifically described with reference 30 to the drawings which accompany and form part of this specification.

Of said drawings: Figure 1 represents a side elevation of a machine illustrating the printing mechanism, of the type of machine shown in the patent to Thos. Carney No. 683,877, issued Oct. 1st, 1901, with my improvements applied thereto. Fig. 2 represents a detail end elevation of the punch, its operating means, and the feed devices for 40 the sales strip, with the electric circuits shown in diagram. Fig. 3 represents a detail top view of a portion of the sales strip after being printed and punched. Fig. 4 represents a transverse sectional view, 45 partly broken away, through the type of machine above mentioned, showing the connections between the operating mechanism and the type carriers; and Fig. 5 represents a detail front elevation of the type carriers 50 and the coöperating mechanism.

In different types of cash registers at

present in use, it is customary to provide mechanism whereby the proprietor may go to the machine and turn the detail strip forward so as to leave a blank portion upon 55 the strip when leaving his place of business; and to again turn the strip forward upon his return, by going to the machine and turning a certain thumb knob, so that the intermediate sales will be located between two blank portions of the strip. The drawbacks, however, to this form of operation are, that the bar-tender, clerk or other operator of the machine is aware that the strip has been turned forward, and for this 60 reason is put on his guard if he is inclined to be dishonest and will not tamper with the machine at that time. If the proprietor should leave the premises at any time without turning the strip forward, through neglect or oversight, the operator would know that this safeguard was not present and that he would be less liable to detection in the practice of certain dishonest manipulations. 65 The present invention, however, is designed 70 so that the proprietor may space the detail strip of the machine without the knowledge of the operator and without going near the machine at all. He not only spaces the strip, but he designates on the strip the time 75 that he leaves and the time that he returns; so that should he leave the premises several times, he will know just what hours he was absent by the final record on the strip, which he may remove after the close of business. 80 85

The operating keys 1, which are arranged in banks, actuate different distances registering frames 2, of which there is one for each bank of keys; and this variable movement is transmitted to type carriers 3 by means of 90 segments 4, pinions 5 and nested sleeves 6. The keys 1 also actuate a universal bar 7, the reciprocatory movement of which is converted into a rotary movement of the shaft 8 by a double faced rack 9 and pinion 95 10. The right hand trunnion 11 of the universal bar 7 extends through the casing 12, and has rigidly secured thereto an arm 13 which carries a spring pressed pawl 14 for engaging the teeth of a ratchet wheel 15, to 100 advance the latter one step upon each operation of the machine.

A sales strip supply roll 16 is suitably mounted upon the casing, and the strip 17 is led from said roll over a table 18 to a storage roll 19 which is fastened to a stub shaft 20 secured to the ratchet wheel 15. It will be seen from the above description, that upon each operation of the machine the strip 17 will be fed from the supply roll 16 over the table 18 to the storage roll 19. The table 18 is suitably cut away so that an impression can be made upon the sales strip 17 from the type carriers 3, through an intervening inking ribbon 20 by a platen 20^a, which in turn is actuated by a suitable cam 21 secured to the rotary shaft 8. All of the above mechanism is fully shown and described in the aforementioned patent, reference to which may be had for a detail description of same.

It is often desired by proprietors of business establishments to ascertain the number and amount of transactions during certain parts of the day, such as before their arrival in the morning or during their absence at any time throughout the day. I have accomplished this result by the following means. The sales strip 17 is wider than the inking ribbon 20 and the carriers 3, as shown in Fig. 5; and just below the outer edge of said strip is a pin 22 carried by a plunger 23 mounted in a suitable guide 24 secured to the casing. This pin and plunger are normally held out of engagement with the strip 17 by a coil spring 25, which surrounds said plunger and has one end in contact with a pin 25^a carried by the plunger and the other end abutting against the upper end of the guide 24. A lever 26, which is approximately centrally pivoted upon the casing 12, has attached to its forward end a spring pressed pawl 27 which engages and rotates the ratchet wheel 15 when the said pawl is reciprocated. To the rear end of the lever 26 is attached a vertical arm 28 secured to a core 29 of a solenoid 30 secured to the casing 12. This core is normally forced upwardly out of the solenoid 30, by a coil spring 31 located in the bottom of said solenoid as shown in Fig. 1. The plunger 23 rests upon a lateral extension 32 of the lever 26, so that when the core 29 is drawn downwardly against the tension of the spring 31 by energizing the solenoid 30, the plunger will be forced upwardly to perforate the sales strip 17; and as the solenoid is deenergized the spring 31 located in the bottom of said solenoid will return the lever 26 and its connected parts to normal position against a stop pin 32^a mounted upon the register frame, and thereby rotate the ratchet wheel 15, and consequently the storage roll 19, by means of the pawl 27. Supported upon the same shaft as the type carriers 3, is a disk 25^b against which the pin 22 strikes when perforating the strip. A

push button 33, as shown in Fig. 2, for energizing the solenoid 30, is arranged to be located at any distant point, and is connected to a battery 34 and the magnet 30 by wires 35, 36 and 37.

While an operation of the push button 33 feeds the paper and perforates its outer edge, it will be seen by reference to Fig. 3 that a blank space will be left where the printing usually occurs when said push button is operated; and by means of these blank spaces the sales during any certain period may be ascertained, as for example: the proprietor upon leaving his place of business, say for instance at three o'clock, will operate the push button three times, which will energize the solenoid 30 and rock the lever 26 the same number of times. Each reciprocatory movement of the lever 26 will perforate and feed the strip, as hereinbefore described. During his absence the sales that occur will be recorded in the usual manner, and as will be seen by reference to Fig. 3 they follow the blank space caused by the operation of the push button 30. Immediately upon his return the proprietor operates the push button a number of times to correspond to the hour of the day, in this instance four. This manipulation of the push button perforates and feeds the strip in a similar manner to that already described. The amounts shown on the strip between the perforations, are the amounts of the various sales made during his absence, or between the hours of three and four.

It will be seen that the first operation of the punch will perforate the paper opposite the last amount recorded, while the first amount recorded after the last perforation will be below the said perforation. This is because of the fact that upon the regular operation of the machine an impression is taken after the feed of the strip, while the solenoid perforates the strip and then feeds it. I have also provided means for automatically closing the circuit once every hour throughout the business day, by an automatic circuit closing arm 33^a which is connected in circuit to the wire 37 and is adapted to pass over and contact once each hour with a contact stud 33^b. Any suitable clock movement 33^c may be connected to the arm 33^a, to give it a movement corresponding to the hour hand of the clock. By this means the detail strip will be moved one space upon the even hour; each hour during the entire day.

It is to be understood that instead of perforating the strip, a suitable platen may be used in place of the pin, to take an impression upon the strip from a type carried by the disk 25^b, in which case the ink ribbon would be extended under the disk.

It will further be observed that as the circuit is closed every hour by the clock, the

strip will be spaced throughout the entire day once during each hour; and the proprietor knowing the time at which his premises were opened, can readily determine 5 between what hours any particular sale occurred during the day. It will not be necessary, of course, for him even to enter into this calculation if he thinks to push the button and perforate the strip at the desired 10 hour upon leaving and returning.

The action of the solenoid is practically noiseless, and any moving parts that contact, in the auxiliary feed devices are provided with suitable felt or rubber washers, to prevent any noise such as would indicate to the 15 operator of the machine that the strip had been fed.

The clock and circuit closing button are located at any convenient position on the 20 premises entirely out of sight of the operator of the machine. Where the proprietor lives on the premises, the button and clock are preferably located in his living rooms. If the proprietor has any occasion to wish 25 to know when out of his sales room, just what particular amount is registered following the entry of a certain customer, he has simply to operate the button after the customer goes in, and then again after the 30 customer leaves, which will of course space the strip in such a manner as to indicate what was registered while the customer was present.

Having thus described my invention, what 35 I claim as new and desire to secure by Letters Patent is:

1. In an accounting machine, the combination with means for spacing a record strip upon the operation of the machine, of mechanism 40 for spacing the strip automatically and periodically.

2. In an accounting machine, the combination with means for feeding and imprinting a record strip, and keys controlling said 45 means, of a clock mechanism and devices controlled by said clock mechanism and having connections for independently feeding said record strip and making an identification thereon.

50 3. In an accounting machine, the combination with means for feeding and imprinting a record strip, and keys controlling said means, of a clock mechanism, and a circuit controlled by said clock and including means 55 for independently and periodically feeding said record strip and making an identification thereon.

4. In an accounting machine, the combination with means for feeding and imprinting 60 a record strip, and keys controlling said means, of a clock mechanism, devices controlled by said clock mechanism for independently feeding said record strip and making an identification thereon, and an auxiliary manually actuated device also con-

trolling said independent feeding and identifying devices.

5. In an accounting machine, the combination with means for feeding and imprinting a record strip, and keys controlling said 70 means, of a clock mechanism, a circuit controlled by said clock mechanism and including means for independently and periodically feeding said record strip and making an identification thereon, and a shunt to 75 said circuit including a manually actuated auxiliary circuit closing device.

6. In an accounting machine, the combination with means for carrying a record strip, of mechanism for feeding the strip, 80 and an additional mechanism for both feeding and perforating the strip.

7. In an accounting machine, the combination with an operating mechanism arranged to be manually controlled, of record 85 material feeding means coöperating therewith, and means for controlling the record material feeding means from a distance unknown to the operator at the machine.

8. In an accounting machine, the combination with type carriers, of an operating mechanism for controlling the movement of the type carriers and feeding a record strip, and auxiliary means for feeding and perforating the strip. 90

9. In an accounting machine, the combination with type carriers, manipulative devices for controlling the movement of the type carriers and feeding a record strip, and auxiliary means for feeding and perforating the strip. 100

10. In an accounting machine, the combination with type carriers for printing on a record strip, of a lever, a punch for perforating the record strip, a solenoid, and means for energizing the solenoid to perforate the strip through means of the lever and the punch. 105

11. In an accounting machine, the combination with type carriers for printing on a record strip, of a lever for feeding the record strip, a punch for perforating the strip, a solenoid, and means for energizing the solenoid to feed and perforate the strip through means of the lever and the punch. 110

12. In an accounting machine, the combination with means for feeding a record strip automatically and periodically from a distance, of other means for feeding the strip at will from a distance. 120

13. The combination with a recording mechanism, means for feeding a record strip upon an operation of the recording mechanism, additional means for feeding the strip independently of the operation of the recording mechanism, and a motor for periodically actuating the latter means. 125

14. In an accounting machine, the combination with mechanism for printing on a record material, and devices automatically 130

operated as an accompaniment to operation of said printing mechanism for feeding the record material, of an auxiliary mechanism for independently making a record on said record material and connections from said auxiliary mechanism for also feeding said record material.

In testimony whereof I affix my signature in the presence of two witnesses.

WILLIAM H. MUZZY.
